AUTOMOTIVE VEHICLE TRUNK GUARD

Robert F. Smith, Grosse Pointe Woods, Mich., assignor to General Motors Corporation, Detroit, Mich., a corporation of Delaware

Application June 25, 1949, Serial No. 3,536

Term of patent 3½ years

(Cl. D14—6)

To all whom it may concern:

Be it known that I, Robert F. Smith, a citizen of the United States, being a resident of Grosse Pointe Woods, County of Wayne, State of Michigan, have invented a new, original, and ornamental Design for an Automotive Vehicle Trunk Guard, of which the following is a specification, reference being made to the accompanying drawing forming a part thereof.

In the drawing:

Figure 1 is a perspective view showing my new design for an automotive vehicle trunk guard in solid lines, with conventional supporting means therefor shown in dotted lines for illustrative purposes only.

Figure 2 is a plan view of the trunk guard of Figure 1.

Figure 3 is a front elevational view thereof.

Figure 4 is a side elevational view thereof.

Figures 5 and 6 are sectional views taken on lines 5—5 of Figure 3 and 6—6 of Figure 4 respectively.

I claim:

The ornamental design for an automotive vehicle trunk guard, substantially as shown and described.

ROBERT F. SMITH.
